(57) **CLAIM**

The ornamental design for an audio apparatus, as shown and described.

DESCRIPTION

FIG. 1 is a perspective view of the audio apparatus;
FIG. 2 is a front view thereof;
FIG. 3 is a rear view thereof;
FIG. 4 is a left side view thereof;
FIG. 5 is a right side view thereof;
FIG. 6 is a top plan view thereof;
FIG. 7 is a bottom plan view thereof; and,
FIG. 8 is a perspective view showing an example of the usage
of the subject design which is connected to a Docking System.

The broken lines are for illustrative purposes only and form
no part of the claimed design.
